HARRY J. RUMPF, OF HALETHORP, MARYLAND, ASSIGNEE OF OMY-HALE TO LEWIS H. FEELES, OF WESTFIELD, NEW JERSEY.

RELIEF-VALVE.

1,102,549.

Specification of Letters Patent.

Patented July 7, 1914.

Application filed May 9, 1912. Serial No. 696,273.

To all whom it may concern:

Be it known that I, HARRY J. RUMPF, a citizen of the United States of America, residing at Halethorp, in the county of Baltimore and State of Maryland, United States of America, have invented certain new and useful Improvements in Relief-Valves; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in relief valves for hot water heating systems, and more particularly to that class of hot water systems wherein the water is maintained under a pressure in addition to its natural hydrostatic head.

The device embodying my invention therefore employs a mercury seal for the movable member, as is customary.

The device is simple, efficient, and reliable in operation under all conditions of service.

Hitherto it has been necessary in similar devices to connect the pressure regulator in the line below the expansion tank of the hot water system. This is often impracticable and my device may be attached to the side of the expansion tank or on top thereof, so that an existing hot water system not under auxiliary pressure may be readily converted into a system using auxiliary pressure without disturbing the installation, and, by virtue of being able to connect the overflow to the side or top of the expansion tank as well as in the customary position, there will always be sufficient space to accommodate the overflow device.

In the drawing, which shows the overflow device in vertical section, 1 represents the water pipe leading to the overflow, which has a threaded connection in the cast iron or other metal bottom 2 of the overflow device. Secured to the body 2 by a threaded connection is the body of the casting comprising the tubular portion 3 having at its upper end an inclined wall 4 forming the bottom of an enlarged chamber 5. The portions 2, 3, 4 and 5 may be cast in one piece, if desired. The chamber 5 is

closed by a screw-cap 6, and is provided with a threaded nipple 7.

Within the casing 3 is the water inlet pipe 10 for the casing, having a screw connection with the bottom 2 and forming a continuation of the inlet pipe 1. This pipe extends slightly above the shoulder formed between the conical or inclined walls 4 and the tubular portion 3 of the casing.

Concentric with the portion 3 of the casing and with the pipe 10 is a bell 11 having a head 12 of slightly larger diameter than the portion 3 of the casing. The lower face of this head has its under surface conical or inclined downwardly from the bell 11 to its periphery, as shown at 13. The head is provided with a screw cap 14 provided with an elongated stem 15, angular in section, for the engagement of a wrench, spanner, or other tool for removing the cap. The cap has a downwardly projecting flange 16 threaded on the outside and beveled at 17 on the inside, and forms a cap for the reception of a vulcanized fiber, rubber, or other packing disk 18.

The bell has its lower portion immersed in a mercury seal 19, and may be loaded to any desired extent by means of removable weights, as 20, provided with a central hole, so that they may be placed over the stem 15.

As illustrated, the overflow is intended for connection to the side of the expansion tank. An increase of pressure in the system drives the water against the air trapped in the tank, causing it to rise and pass through pipes 1 and 10. If the pressure is sufficient to lift the bell 11, it will rise until its lower edge leaves the mercury 19, when, under ordinary circumstances, it will, under the sustained pneumatic pressure in the tank, quietly pass down between 10 and 11 and between the mercury seal and the lower edge of the bell 11, rising between 11 and 3 to the overflow pipe 9. Should the pressure of the water be suddenly increased, some of the mercury is apt to follow the water for the first few seconds into 5, and in so doing meets the deflecting surface 13 and is thrown back onto the conical wall 4, and is prevented from being splashed out through the overflow 9. After the initial rush of water through the device the mercury immediately falls between 3 and 11 to the bottom of 3. Should the expansion in the heating system

be so great that water will pass over from the expansion tank to the overflow device, the lift of the bell 11 will, so to speak, increase the volume of pipe 10 before the seal at 19 is broken, so that a certain amount of water will return to the expansion tank and system upon decrease of the expansion. On the other hand, if no water passes to the overflow device from the expansion tank, but 10 only compressed air, a certain amount of air will be returned to the expansion tank, and an equivalent volume of water will be returned from said tank to the system when contraction sets in. The valve 14 being 15 weighted, the volume of mercury in the seal will be increased in proportion to the increase of weight used, and when this valve is lifted by the expansion, the mercury seal prevents a sudden rush of the water or air, 20 the mercury giving way, or "stringing" up between 11 and 3 only after a certain extent of lift of the valve. The mercury also insures an effective seal should there be a small leakage between the packing 18 and 25 the end of pipe 10.

I claim—

1. A relief valve comprising a casing having a body portion and an upper enlarged chamber connected thereto by an inclined wall, a water inlet pipe extending concentrically through the body portion and terminating slightly above the lower edge of said inclined wall, a bell normally resting on said inlet pipe and terminating near the 30 bottom of the casing and forming, with the casing and inlet pipe, concentric annular 35 chambers which connect the pipe with the upper enlarged chamber, a mercury seal in the bottom of the casing normally closing communication between said annular chambers, said bell having a head extending over the lower portion of the inclined wall and coöoperating with the latter to return mercury forced from the casing back to the latter.

chambers which connect the pipe with the upper enlarged chamber, a mercury seal in the bottom of the casing normally closing communication between said annular chambers, said bell having a head extending over the lower portion of the inclined wall and coöoperating with the latter to return mercury forced from the casing back to the latter. 40

2. A relief valve comprising a casing having a body portion and an upper enlarged chamber connected thereto by an inclined wall, a water inlet pipe extending concentrically through the body portion and terminating slightly above the lower edge of said inclined wall, a bell normally resting on said inlet pipe and terminating near the bottom of the casing and forming, with the casing and inlet pipe, concentric annular 55 chambers which connect the pipe with the upper enlarged chamber, a mercury seal in the bottom of the casing normally closing communication between said annular chambers, said bell being provided with a head 60 overhanging the lower portion of the inclined wall, the underface of the head being inclined downwardly and outwardly from the bell for the purpose specified.

In testimony that I claim the foregoing as 65 my invention, I have signed my name in presence of two subscribing witnesses.

HARRY J. RUMPF.
